[57] CLAIM

The ornamental design for picnic/party cooler, as shown and described.

DESCRIPTION

FIG. 1 is a three-quarter front pictorial view of a first embodiment of a picnic/party cooler according to my new design;

FIG. 2 is a front elevational view of the first embodiment and is also a mirror image of a rear elevational view;

FIG. 3 is a left side elevational view of the first embodiment and is also a mirror image of a right side elevational view;

FIG. 4 is a top plan view of the first embodiment;

FIG. 5 is a bottom plan view of the first embodiment;

FIG. 6 is a three-quarter front pictorial view of a modified design for the first embodiment of a picnic/party cooler according to my new design;

FIG. 7 is a three-quarter front pictorial view of a second embodiment of a picnic/party cooler according to my new design;

FIG. 8 is a front elevational view of the second embodiment and is also a mirror image of a rear elevational view;

FIG. 9 is a left side elevational view of the second embodiment and is also a mirror image of a right side elevational view;

FIG. 10 is a top plan view of the second embodiment;

FIG. 11 is a bottom plan view of the second embodiment; and,

FIG. 12 is a three-quarter front pictorial view of a modified design for the first embodiment of a picnic/party cooler according to my new design.

The broken line showing the handle recesses is for illustrative purposes only and forms no part of the present design.
